UNITED STATES PATENT OFFICE

2,355,536

VENTILATOR APPARATUS

Langdon M. Jenness, Chicago, Ill.

Application June 26, 1942, Serial No. 448,537

1 Claim. (Cl. 98—99.8)

This invention relates generally to ventilator apparatus and in particular to a ventilator apparatus of a type adapted to be extended across a window frame between the bottom rail of a window and the sill for such window.

Ventilators of this type in the prior art generally include an extensible vented body member having the bottom resting on the window sill and the top in abutting engagement with the bottom window rail. These ventilators are not entirely satisfactory because rain generally passes between the top of the ventilator and the window and runs down the inner side or face of the ventilator to the window sill, from where it usually drains under the stool and onto the wall in which the window is located. Any water passing through the ventilator vents also runs down the inner face of the ventilator to augment the leakage at the top of the ventilator. This condition is aggravated when the window is equipped with weather stripping including an upstanding tongue or weather strip on the window sill adapted to be received in a groove in the bottom rail of the window when the window is in a closed position. The bottom of these prior art ventilators is usually positioned to the inside of the weather strip and adjacent the window stool. In other words the ventilator bottom rests on the sill intermediate the weather strip and the window stool. Upon the occurrence of water leakage, as above explained, the water is prevented from flowing off the window sill toward the outside of the window by the weather strip which cooperates with the window stool to form a water pocket or reservoir at the bottom of the ventilator. The water from the reservoir drains under the stool, it being understood that in the usual prior art ventilators the water is able to pass between the bottom of the ventilator and the window sill. Further any water running down the outer side of the ventilator also collects in this reservoir to drain under the stool and onto the wall to the inside of the window.

It is an object of this invention, therefore, to provide an improved ventilator apparatus.

Another object of this invention is to provide ventilator apparatus adapted to be installed between the bottom rail of the window and sill therefor which prevents water leakage at the top and drains any water running down the inner face thereof to the outside of the window. Leakage of water about the window stool is thus positively eliminated.

A further object of this invention is to provide a ventilator for a window which is adapted to

cooperate with a weather stripping for the window to prevent any leakage of water to the inside of the window.

A feature of this invention is found in the provision of a ventilator for a window in which a water carrying portion co-extensive in length with the ventilator is formed at the bottom thereof to collect any water running down the inner face thereof. Openings or seep holes in a wall of 10 the water carrying portion drain the water thus collected to the outside of the window and away from the window stool.

Further objects, features and advantages of this invention will become apparent from the following description when taken in connection with the accompanying drawing in which:

Fig. 1 shows the assembly of one form of the invention with an associated window;

Fig. 2 is an enlarged sectional view as seen along the line 2—2 of Fig. 1;

Fig. 3 is a fragmentary view in perspective showing the structure of the bottom portion of the ventilator of this invention as illustrated in Figs. 1 and 2.

With reference to the drawing there is shown in Figs. 1 and 2 a window or sash 10 of double hung type having a lower rail 11 and stiles 12 vertically slidable in a window frame 13 having a sill portion 14. The window is illustrated as being weather conditioned with a groove 16 formed in the bottom rail 11 adapted to receive therein, when the window is in a closed position, an upstanding tongue or weather strip 17 carried on the sill 14. The ventilator of this invention is adapted, when the window is in an open position, to be installed between the lower rail 11 and the sill 14.

The ventilator includes a body portion comprised of a pair of extensible sections or plates 18 and 19 which are in telescoped engagement, as indicated at 20 in Figs. 1 and 3, at the tops and bottoms thereof. Each ventilator section is provided with a handle portion 21 on the inner side thereof and vents 22 which are punched or stamped out therein, the punched out portions being projected from the outer face of the ventilator sections in a usual manner. The upper part of the ventilator, as best shown in Fig. 2, is of a somewhat angulate shape with a straight top portion 23 parallel to the main body portion of the ventilator but off set away from the inner face thereof by a connecting portion 25. The lower part of the ventilator body portion is integrally formed on the inner face there-

of with a substantially channel or trough shaped portion 24.

In the assembly of the ventilator the top portion 23 is positioned within the groove 16 of the window rail 11 with the channel portion 24 located adjacent the weather strip 17 and to the outside thereof. By means of the handles 21 the sections 18 and 19 are moved away from each other and into engagement with corresponding sides of the window frame 13 so as to extend completely thereacross. The ventilator is held in its assembly position by pushing the window down thereon in a well known manner. With the top portion 23 within the groove 16 the outer side 30 of the window rail 11 overhangs such portion while the under side engages substantially the connecting portion 25. This relative assembly of the ventilator top with the window rail 11 positively prevents any leakage of water between the window and the ventilator. Any water which might pass through the vents 22 and onto the inner face of the ventilator travels downwardly on this face into the water carrying portion 24 at the bottom thereof. Drain or seep holes 26 (Figs. 2 and 3) are provided in the body portion of the ventilator, which forms an outer wall for the water carrying portion, for draining water therefrom to the outside of the window and away from the weather strip 17. By virtue of the ventilator bottom being located adjacent but to the outside of the weather strip 17, such strip cooperates with the liquid carrying portion to prevent any leakage of water inwardly thereof toward the window stool 27. In other words any water which might run down either side of the ventilator is retained to the outside of the weather strip 17, with any water collecting between the weather strip and the ventilator being immediately drained to the outside of the window through the water passages in the bottom of the ventilator. As a result any water running down either the inner or outer face of the ventilator

is positively prevented from traveling inwardly beyond the weather strip 17 so as to prevent any seepage of water about the stool 27 and onto the wall 28 to the inside of the window 10.

From a consideration of the above description and the drawing, therefore, it is seen that the invention provides a ventilator which is of a simple and rugged construction, adapted to be easily assembled in windows with or without weather conditioning provisions, and which functions to positively eliminate water leakage inwardly of the window with which it is associated.

Although the invention has been specifically described with reference to a preferred embodiment thereof it is to be understood that it is not to be so limited since modifications and alterations can be made therein which are within the full intended scope of this invention as defined by the appended claim.

I claim:

In ventilator means for a window structure with a movable sash having a groove in the bottom rail thereof and said window structure having an upstanding tongue on the sill therefore adapted to fit into the groove to provide a weather seal when the window sash is closed, a ventilator for fitting between the sash and sill when the window is open comprising telescoping plates having ventilating openings therethrough, said ventilator being extensible across said window opening and having a top edge portion receivable in the window sash groove to retain the ventilator at the top and close the window opening, said plates each having an in-turned channel-like portion at the bottom thereof adapted together to be positioned to the outside of the upstanding tongue, and said channel-like portions having a drain opening therein opening to the outside of the plates to drain away from said channel-like portion any water collecting therein from the inside of the ventilator.

LANGDON M. JENNESS.
